UNITED STATES PATENT OFFICE

VIKTOR JERECZEK, OF LICHTENBERG, NEAR BERLIN, GERMANY, ASSIGNOR TO
SCHNELLPRESSENFABRIK AKTIENGESELLSCHAFT HEIDELBERG, OF HEIDELBERG,
GERMANY, A CORPORATION OF GERMANY

PLATEN PRINTING PRESS

Application filed May 20, 1924, Serial No. 714,694, and in Germany May 28, 1923.

My invention relates to platen printing presses and more particularly to a device for moving the platen of such presses.

With platen printing presses, especially 5 with such of the type known as Boston- presses, in which the platen swings on an axle lying about in its middle, the platen is moved by means of a connecting-rod actuated by the driving shaft of the machine. This known 10 arrangement is possessed of the drawback that, with high-speed machines, there does not remain sufficient time for the work-piece to take up the print, because the period of printing is too short therefor, which entails 15 the necessity to obviate surpassing a certain limit of speed as otherwise the imprints obtained are not of workmanlike quality.

The object of my invention is to obviate 20 said drawbacks and I attain the effect intended by providing a toggle-joint lever connected at its joint with the above-mentioned connecting-rod, whereas the free end of one 25 of its members is connected with the machine frame, and the free end of the other member is connected with the platen. Owing to this 30 arrangement and combination of the parts mentioned, not only the compressive forces are transmitted to the frame of the printing press, which is counter to what takes place 35 in printing presses of the known types, but, principally, the period of time during which the work-piece is pressed against the matter required for the printing is considerably longer, as the members of the toggle-joint 40 lever remain aligned during a comparatively long part of the path of the driving crank. The work-piece, i. e. the printing sheet, has, therefore, sufficient time to take up the ink, and the printing-presses provided with a 45 toggle-joint lever arranged in the manner stated can run with a considerably higher speed so that their output is correspondingly greater. Besides, the platen with the work-piece is pressed against the matter 50 always appropriately strong as it is possible, owing to the suitable arrangement of the toggle-joint lever, to re-adjust it when any one of the driving-parts concerned has been worn off, which permits also to regulate the strength of 55 that pressure.

My invention is illustrated, by way of example, in the accompanying drawing in which Figure 1 is partly a side-view of the platen and the toggle-joint lever and partly a vertical section through a few adjacent stationary parts of the printing-press, and Figure 2 is partly a plan of the toggle-joint lever and partly a horizontal section in line I—I of Fig. 1.

1 is the main driving shaft of the printing-press, and 2 a crank affixed thereto and connected by the connecting rod 3 with the toggle-joint lever 4/5, the member 4 of which is connected with a sleeve-shaped bearing 7 by a pivot 14, whereas the member 5 of the 55 toggle-joint lever is connected with the downwardly extending lever arm 8^a of the platen 8 by a pivot 15. The platen is carried by an axle 9 supported in the frame 6 of the printing-press. The bearing 7 is secured to this 60 frame, so that the abutment-pressure is taken up directly by the frame 6 whereby the rotary members are relieved and less subjected to 65 wear and tear.

Owing to the insertion of the toggle-joint 70 lever between the driving shaft 1 and the platen 8 the length of the printing period is materially longer than with direct engagement of the connecting-rod at the platen, because the toggle-joint lever is completely 75 straight when the crank 2 and the connecting-rod 3 are nearly in alignment and the wrist of the crank is passing the dead center so that the toggle-joint lever remains in its straight 80 position during the passing of the dead center, as will be understood.

When, owing to wear and tear of the joints or the like the pressure which the platen exerts on the printing face 10 is no more sufficient, it is easily possible to make up therefor by re-adjusting the bearing 7 which is attached to the frame 6 by a strong pivot 13 which is turnably supported in the frame and can also be re-adjusted longitudinally 90 therein, firstly, by means of a bolt 11 which is screwed into the pivot 13 from the rear side of the frame and the head 16 of which bears against a washer 17, as shown; secondly, by means of any one of washers 12 of different thickness, of which that having the suitable 95 100

thickness is inserted between the bearing 7 and the adjacent face of the frame-boss 6^a in which the pivot 13 is supported. Owing to this pivot being rotatable in the boss 6^a, the bearing 7 can adjust itself, automatically, into that position in which the pivot 14 lies parallel to the other pivots of the toggle-joint lever. The bolt 11 is drawn fast when proper spacing-washer 12 has been inserted and the 10 automatic re-adjustment of the pivot 13 has taken place, as described.

I claim:

1. In a mechanically driven platen printing press, in combination, a press frame, a main driving shaft journaled in said frame and arranged for rotating in one direction with uniform velocity, a crank affixed to said shaft, a platen having a lever arm, an axle horizontally arranged in said frame and on which said platen is arranged for rocking movement, a toggle joint lever having one arm connected to the lever arm of said platen, the other arm being turnable in a bearing connected to said frame, said bearing being turnable on a horizontal axis, a connecting rod having its one end connected to said crank and its other end connected to the central joint of said toggle, said crank and toggle lever connection being arranged to bring said 25 platen to its printing position, when said toggle lever is fully straightened and said crank is at dead center.
2. In a mechanically driven platen printing press, in combination, the frame of the press, the main driving shaft journaled in said frame and rotating in one direction with uniform velocity and having a lever arm, a crank affixed to said shaft, the platen arranged for rocking movement on an axle horizontally arranged in said frame, a toggle joint lever having one arm connected to the lever arm of said platen, the other arm being turnable in a bearing connected to said frame, said bearing having a horizontal pivot journaled 40 in the frame of the press, a screw for horizontally shifting said pivot and bearing, and a spacing member arranged on said pivot between the frame and said bearing, a connecting rod having one end connected to said crank and its other end connected to the central joint of said toggle, said crank and toggle lever connection being arranged to bring said platen to its printing position, when said toggle lever is fully straightened and said 45 crank is at dead center.

In testimony whereof I have affixed my signature.

VIKTOR JERECZEK.
